PLAYGROUND MERRY-GO-ROUND

Claude W. Ahrens, Grinnell, Iowa

Filed Jan. 13, 1961, Ser. No. 63,546

Term of patent 14 years

(Cl. D34—5)

FIG. 1 is a top plan view of a playground merry-go-round showing my new design;

FIG. 2 is a side elevational view thereof with the tubular base broken away to indicate indeterminate length; and

FIG. 3 is a reduced sectional detail perspective view showing the configuration of the recesses in the merry-go-round.

Each recess in the dome shape body member includes a bottom wall of a semi-circular shape having a marginal vertical wall which terminates in the convex exterior surface of the body member.

I claim:

The ornamental design for a playground merry-go-round, substantially as shown and described.
